UNITED STATES PATENT OFFICE.

WILLIAM LIVINGSTON DENIO, OF ROCHESTER, NEW YORK, ASSIGNOR OF ONE-HALF TO HOBART F. ATKINSON, OF ROCHESTER, NEW YORK.

AUXILIARY FIRE-ALARM SYSTEM.

SPECIFICATION forming part of Letters Patent No. 761,636, dated May 31, 1904.
Application filed January 20, 1904. Serial No. 189,922. (No model.)

To all whom it may concern:

Be it known that I, WILLIAM LIVINGSTON DENIO, a resident of Rochester, in the county of Monroe and State of New York, have invented certain new and useful Improvements in Auxiliary Fire-Alarm Systems; and I do hereby declare the following to be a full, clear, and exact description of the invention, such as will enable others skilled in the art to which it pertains to make and use the same.

This invention relates to fire-alarm apparatus of the class employing one fire-alarm transmitter for a selected building or district and one or more manual and thermostatic circuit-changers in different parts of each building or district, whereby the box can be operated from either of several places.

In the accompanying drawings, Figure 1 is a front view of the auxiliary box with the cover broken away. Fig. 2 is a view at right angles to Fig. 1, the cover and box being broken away on the central vertical transverse plane. Fig. 3 is a view of the escapement and certain releasing parts detached. Fig. 4 is a front view of the electric resistance device. Fig. 5 is a horizontal section just above the spring over the releasing push-rod, and Fig. 6 is a diagram of circuits and connections.

Referring first to the diagram Fig. 6, C O indicates a central office where is a source of current for any desired number of metallic circuits 1 1, (one only being shown,) leading to distant fire-alarm boxes 2. Numeral 3 indicates a third wire, called the "auxiliary" wire, which is connected to one side of circuit 1 and which is substituted for said side when either of the manual or automatic thermostatic circuit-controllers 4 is operated.

The auxiliary fire-alarm box is shown on Sheets 1 and 2. The operating mechanism is mounted on an insulating-plate 6 on a frame or body having a cover 8, which when on, pushes (by pin 10) pin 9 and its slide 11 to the left, engaging and holding the flange at the top of the glass cover 12, which cover is over the push 13, which is normally down, but which can be pushed up when the glass cover is removed or broken until it is locked by spring-arm 14 falling into groove 12' in said

push 13. The inner end of part 13 when moved inward moves against spring 15, tilting the arm 16, pivoted at 17, and carrying beyond the pivot armature 18 of magnet 19, connected in the auxiliary wire 3. The armature when moved by the push 13 or by the magnet releases the escapement 20 of the motor, allowing it to turn the signal-wheel 22, breaking and making the main current. Movement of the armature also allows pivoted lever 23 to swing over the armature to hold it down. This lever operates in the same way when the armature is moved by the magnet 19. When the motor is wound by moving arm 24 to the position of Fig. 1, the end 25, insulated from the lever, holds spring 26 against spring 27, which keeps the main line normally closed through the box, the connection being from line to post 28, through said springs to post 29, to line. When the motor is released, as above described, part 25 moves from spring 26, which moves down, separating from spring 27 and connecting springs 30 31, as seen in Fig. 6.

The signal-box, with the releasing magnet and armature, constitutes an auxiliary box, started at the box itself by push 13 or from a distance by operation of either of the manual and automatic controllers 4 or by an ordinary hand-switch 34, by which the circuit may be closed to test its condition at any time or to send an alarm before the thermostats operate. The dotted position of the switch is the normal one. After the movement has started the circuit is opened by a special notch 30' in the signal-wheel to give one false blow in the central-office receiver before the regular signal begins to be sent. At the same time the resistance of the tripping-magnet is cut out.

The resistance device which spans the local signal-lamp 27' at the auxiliary box consists of an insulating body 32, having a resistance-conductor 33 extending back and forth thereon.

It will be seen that in removing the cover 8, Fig. 5, the tension of spring 14 is released to guard against accident of starting the box. In Fig. 6 an ordinary manual switch 34 is

shown, the switch-arm being normally in dotted position holding wire 1 closed, but when operated changing the circuit to auxiliary wire 3. This is also the operation if a manual 5 or automatic switch is used. Lever 23 may be thrown forward by spring 23' on its pivot.

The manual and automatic circuit-controller above referred to is described and claimed in my application of even date herewith, Serial 10 No. 189,924.

Having described my invention, what I claim as new, and desire to secure by Letters Patent, is—

1. The combination of an auxiliary fire-alarm box, a central office, a normally closed circuit between said box and office, a battery in the circuit at the office, springs 26, 27, at the box, means normally holding the springs together closing said circuit, a box-releasing magnet, an auxiliary wire extending from the box to the place to be protected, normally open circuit-controllers between the auxiliary wire and the normally closed circuit, a magnet 19 in the auxiliary wire, the latter being normally 15 open at the circuit-controllers, means operated by said magnet for releasing the box and means at the box for separating the springs 26, 27, in the normal circuit, and closing a signal-circuit including the auxiliary wire and a part of the normally closed circuit, said signal-circuit cutting out said magnet.

2. The combination of an auxiliary fire-alarm box, a central office, a normally closed circuit between said box and office, a battery 35 in the circuit at the office, contact-springs 26, 27, 30, and 31 at the box, two of said springs, 26, 27, being normally connected closing said

circuit, a box-releasing magnet, an auxiliary wire extending from the box to the place to be protected, normally open circuit-controllers between the auxiliary wire and the normally closed circuit, a magnet 19 in the auxiliary wire, the latter being normally open at the circuit-controllers, means operated by said 40 magnet for releasing the box, and means at the box for separating said contact-springs 26, 27 of opening the normal circuit, and for connecting contact-springs 26, 30, 31, closing an alarm-circuit. 50

3. The combination of an auxiliary fire-alarm box, a central office, a normally closed circuit between said box and office, a battery in the circuit at the office, springs 26, 27 at the box, means normally holding the springs 55 together closing said circuit, a box-releasing magnet, an auxiliary wire, normally open circuit-controllers between the auxiliary wire and the normally closed circuit, magnet 19 in the auxiliary wire, the latter being normally 60 open at the circuit-controllers, means operated by said magnet for releasing the box and separating springs 26, 27 in the normal circuit and closing the signal-circuit, a circuit-breaking wheel and spring for the signal-circuit, a wheel having a preliminary signal notch in advance of the number-sending notches. 65

In testimony whereof I have signed this specification in the presence of two subscribing witnesses. 70

WILLIAM LIVINGSTON DENIO.
